COMBINED AWNING AND SHUTTER

James J. Morrison, Saratoga Springs, N.Y.

Application June 28, 1947, Serial No. 757,721

5 Claims. (Cl. 160—40)

1

My invention relates to awnings and particularly to awnings formed of rigid material, such as sheet metal. More particularly, it relates to improvements in such awnings whereby they are rendered collapsible or foldable to facilitate storage and shipping, and which, when a house is closed for the season, or any other reason, may be down-folded to form a closure or shutter for the window to which they are attached.

One of the objects of my invention is to provide an awning formed of sheet metal or other rigid sheet material which may be painted to simulate an ordinary fabric awning; which will be ornamental in configuration; and which may be folded down and secured to the window frame to form a closure or shutter for the window in the event of severe storms, such as hurricanes, or to form a closure for the window when the house is unoccupied.

Another object is to provide an awning of such design which is formed of rigid sheet material and which may be folded into a comparatively small compact unit to facilitate the shipping or storage thereof.

A further object is to provide an awning of the character described which will have an indefinitely long life and be free from corrosion or disintegration due to an indefinitely long exposure to the elements.

With these objects in view, my invention includes the novel elements and the combinations and arrangements thereof described below and illustrated in the accompanying drawing in which—

Fig. 1 is a perspective view showing a fragmentary portion of a building having a window therein with which my awning is associated;

Fig. 2 is a side elevation view of the awning;

Fig. 3 is a vertical section through the awning;

Fig. 4 is a front elevation view of my device when folded in shutter-forming position;

Fig. 5 is a side view of Fig. 4;

Fig. 6 is a section of Fig. 4 in the plane 6—6; and

Fig. 7 is a section of Fig. 4 in the plane 7—7.

Referring to the drawings—

My awning comprises a main portion 1 which is provided at the top with a hinge 2 adapting it to be secured to the front of a building or the top of a window frame 3 so that it may be swung down from the normal, awning-forming position shown in Figs. 1, 2 and 3 to the shutter-forming position shown in Figs. 4—7, inclusive. Preferably, but not necessarily, integral with the main portion of the awning 1 are comparatively

5 short, side valances 4 which are adapted to close the spaces between the building or window frame and the main portion of the awning, at the sides thereof, when the main portion is down-folded, as shown in Figs. 4—7, inclusive.

10 The awning is also provided at the sides with valances 5 which, in normal awning-forming position, depend below the valances 4, and which are connected to the main portion of the awning by hinges 6 adapting them to be infolded to underlie the main portion 1 of the awning when the awning is in shutter-forming position, as shown in Figs. 4—7, inclusive. Pivotedly secured at 7 to each of the valances 5 is a brace 8, the 15 free end of which is pivotally secured to a bracket 9 on the window frame and supports the awning in awning-forming position.

10 The main portion of the awning is also provided with a front valance 10 which is secured 20 to the main portion of the awning by means of a hinge 11 adapting it to be swung outwardly into a position approximately coplanar with the main portion of the awning 1 when the awning is in shutter-forming position, as shown in Figs. 25 4—6, inclusive. The front valance 10 is provided with inturned side flanges 12 of a width substantially equal to the side valances 4 in order to form closures for the spaces between the valance 10 and the sides of the house or window frame when the awning is in shutter-forming position.

30 The valances 5 and 10 are normally held in awning-forming relation by means of pins or machine screws 13 extending through the valances 5 and the side flanges 12 of the front valance.

35 In the case of most windows, the awning cannot be made long enough to form a complete closure for the window, when in shutter-forming position, without impairing the proper appearance of the device, when in awning-forming position. Therefore, in such a case, to form a complete shutter closure for the window, a separate unit 14 may be provided having a top portion 15 adapted partially to underlie the valance 10, as shown at 16 in Fig. 6, downturned side flanges 17 forming extensions of the side closures of the shutter, and a downturned bottom flange 18 forming a closure for the bottom of the shutter and which may be secured to the bottom of the window frame 3 by screws 19 passing through the depending flange 20 which lies against the bottom of said frame.

When in shutter-forming position, the downturned side flanges of the element 15 may be secured to the flanges 12 of the front valance 10

by removing the pins 13 (see Figs. 2 and 3) and inserting them in the positions shown at 13' in Figs. 4 and 5. In order to prevent the pins 13 from being withdrawn from the outside of the shutter, cotter pins 21 are passed through holes in the pins 13, 13', as shown in Fig. 6. In order to secure the main portion of the awning in shutter-forming position, the pins 22 which secure the braces 8 to the brackets 9 of the awning are inserted through openings 23 provided in the valances 4 and secured in place by cotter pins 24.

From the foregoing, it will be apparent that I have provided a device which will function as an awning and which may be downfolded to form a complete closure for the window. Although the screws 19 may be removed from the outside, it will be apparent that the element 14 cannot be easily raised away from the window frame because it is held down by the front valance 10 and secured to said valance by the pins 13' which cannot be readily pulled out because of the cotter pins 21 on the inside thereof.

I prefer to form my combined awning and shutter of sheet or strip aluminum, depending upon its size, because it is light and substantially non-corrodible.

What I claim is:

1. A folding awning comprising a main portion formed of sheet metal and provided at the top with means adapting it to be secured to a building, side valances formed of sheet metal, a hinge connecting each of said side valances at the top thereof to the under side of said main portion by which said side valances are swingable into positions beneath said main portion, a front valance formed of sheet metal, a hinge connecting said front valance at the top thereof to the under side of said main portion adjacent the front edge thereof by which said valance is swingable between a normal, valance-forming position and a position approximately coplanar with and forming an extension of the main portion of said awning, and means detachably securing said valances together in awning-forming position.

2. A folding awning comprising a main portion formed of sheet metal and provided at the top with means adapting it to be secured to a building, side valances formed of sheet metal, a hinge connecting each of said side valances at the top thereof to the under side of said main portion by which said side valances are swingable into positions beneath said main portion, braces pivotally connected to said side valances and swingable therewith, a front valance formed of sheet metal, a hinge connecting said front valance at the top thereof to the under side of said main portion adjacent the front edge thereof by which said front valance is swingable between a normal, valance-forming position and a position approximately coplanar with and forming an extension

of the main portion of said awning, and means detachably securing said valances together in awning-forming position.

3. A combined shutter and awning comprising a main portion formed of sheet metal and provided at the top with a hinge for securing it to a building above a window and swingable on said hinge from a normal, downwardly and outwardly inclined, awning-forming position to a shutter-forming position offset from and substantially parallel to the front of said building, side valances formed of sheet metal rigidly connected to said main portion and closing the spaces between said building and said main portion when the latter is in shutter-forming position, side valances formed of sheet metal normally depending below said rigidly connected valances but provided at the top thereof with hinges connecting them to the under side of said main portion adjacent the first mentioned valances and swingable by said latter hinges into positions beneath said main portion when in shutter-forming position, a front valance formed of sheet metal, and a hinge connecting said front valance at the top thereof to the under side of said main portion adjacent the front edge thereof, said front valance being swingable between a normal, valance-forming position and a position approximately coplanar with and forming an extension of the main portion of said awning when in shutter-forming position; said front valance being provided with portions at the sides thereof forming space-closing extensions of the first above mentioned side valances when in shutter-forming position.

4. The structure set forth in claim 1 in which braces for holding said awning in awning-forming position on a building are pivotally attached to said side valances and swing therewith beneath said main portion, and said main portion is provided with fixed side valances smaller than and depending from said main portion outside said hinged side valances.

5. The structure set forth in claim 3 in which braces for holding said combined shutter and awning in awning-forming position on a building are pivotally attached to the side valances hinged to the top portion and swing therewith beneath said top portion when in shutter-forming position.

JAMES J. MORRISON.
